UNITED STATES PATENT OFFICE.

JOHN LEITGEB, OF GREAT FALLS, MONTANA.

RAILWAY SIGNAL SYSTEM.

1,071,669.

Specification of Letters Patent. Patented Aug. 26, 1913.

Application filed October 2, 1912. Serial No. 723,535.

To all whom it may concern:

Be it known that I, JOHN LEITGEB, a citizen of the United States of America, residing at Great Falls, in the county of Cascade and State of Montana, have invented new and useful Improvements in Railway Signal Systems, of which the following is a specification.

This invention relates to improvements in railway signal systems and in the present instance has particular application to a block signal system.

In carrying out the present invention, it is my purpose to provide a signal system whereby two trains may signal each other automatically when approaching or following each other within the danger zone, and furthermore, it is my purpose to provide a signal system wherein each train is equipped with a source of energy and a suitable form of signal and wherein the source of energy on each train will influence the signal on the other train in such manner that the engineers of both trains will be advised of the condition of the track. It is also my intention to provide a railway signal system which will embrace the desired features of simplicity, efficiency and durability coupled with cheapness of cost in construction and installation and which will be at all times reliable in use.

With the above and other objects in view, the invention consists in the construction, combination and arrangement of parts hereinafter set forth in and falling within the scope of the claim.

In the accompanying drawing; the figure is a diagrammatic view of my system.

Referring now to the accompanying drawing in detail, T, T' indicate two trains which, in the present instance, are approaching each other within the danger zone. The numeral 1 indicates one line of rails of the trackway, the rails of such line being bonded to form a continuous metallic conductor, while the numeral 2 indicates a conductor suitably supported along the trackway and divided into sections or blocks 3, 3 by means of insulated material 4. Each train, T, T' is equipped with a suitable source of energy as a battery 5 for instance, and a circuit closer 6 composed, in the present instance, of a drum formed of metallic segments 7, 8 and insulating blocks or segments 9, 9 separating the metallic segments and insulating the same one from the other. Any suitable

means may be employed for rotating the circuit closer. In this form of my invention I employ an electric motor 10 having a worm 11 on the armature shaft thereof and meshing with a worm wheel 12 secured to the drum of the respective circuit closer. Leading from one side of each battery 5 is a conductor 13 terminating in a brush 14 bearing upon the drum of the respective circuit closer, while from the opposite side of each battery leads a conductor 15 grounded upon the axle of the engine as at 16. Each train is equipped with a contact roller 17 bearing upon the conductor 2 and connected by way of a conductor 18 with a brush 19 which latter bears upon the drum of the respective circuit closer. Also contacting with the drum of the circuit closer on each train is a brush 20 connected to one terminal of a conductor 21 which latter extends through the windings of an electromagnet 22 and is ground upon the axle of the respective car or engine as at 23.

Arranged upon each train is a suitable form of signal, as a bell 24 disposed within a normally open local circuit including a source of energy as a battery 25 and a circuit closer 26, the latter being held normally in circuit opening position by means of the hooked extremity of an armature 27 disposed within the influence of the respective magnet 22.

In practice, the drums of the circuit closers on the trains are rotated in such manner that the segment 7 of the circuit closer on one train bridges the brushes 14 and 19, while the similar segment on the other train bridges the brushes 19 and 20, as clearly illustrated in the drawing. Assuming the circuit closers to be in the position shown in the figure of the drawing, the battery 5 on train T will supply energy to the magnet 22 on train T' whereby the armature 27 on the last-mentioned train will be actuated to release the circuit closer 26 and so close the local signal circuit. The path of the current from the train T to the train T' may be traced as follows; battery 5 on train T, conductor 13, brush 14, segment 7, brush 19, conductor 18, contact roller 17, conductor 2, contact roller 17 of train T', conductor 18, brush 19, segment 7 of the last mentioned train, brush 20, electromagnet 22, car axle and wheel, line of rails 1, the wheel and axle of train T and conductor 15. In the continued movement of the drums of the

circuit closers under the action of the driving motors thereof, the segment 7 of the circuit closer on train T bridges the brushes 19 and 20, while the segment 8 of the circuit closer on train T' bridges the brushes 14 and 19. Thus the electromagnet 22 on train T is energized with the effect to close the local signal circuit of such train.

From the foregoing description taken in connection with the accompanying drawing, the construction and mode of operation of my invention will be readily apparent. It is to be understood that the circuit closers of the trains are timed or operated in such manner relatively to each other that the brushes 14 and 19 of one train are bridged, while the brushes 19 and 20 of the other train are bridged. Thus, the signals of the trains are energized or operated successively or one after the other.

I claim:

In a railway signal system, a sectional conductor, a continuous conductor, a source of energy carried by each train and having one side in electrical communication with one of said conductors, a circuit closer upon each train comprising a drum embodying

two metallic segments insulated from each other, a motor for rotating said drum, a brush adapted to contact with the segments of said drum and connected with the other side of said source of energy, a second brush bearing upon the drum and electrically connected with the other conductor, a third brush bearing upon said drum and electrically connected with the first-mentioned conductor, a magnet in electrical communication with said last-named brush, and a local signal circuit controlled by said magnet, the circuit closers on the trains being so timed relatively to one another that the first-mentioned brushes of one train are bridged by one segment of the drum, while the second and last-named brushes of another train are bridged by one of the segments of the respective drum whereby the source of energy on one train will energize the magnet on another train.

In testimony whereof I affix my signature in presence of two witnesses.

JOHN LEITGER
